PAIR OF SPECTACLES OR SIMILAR ARTICLE

Edward Rosen, Newark, N. J.

Application May 16, 1952, Serial No. 19,735

Term of patent 14 years

(Cl. D57—1)

To all whom it may concern:

Be it known that I, Edward Rosen, a citizen of the United States, residing in the city of Newark, county of Essex and State of New Jersey, have invented a new, original, and ornamental Design for a Pair of Spectacles or Similar Article, of which the following is a specification, reference being had to the accompanying drawing, forming a part hereof:

Figure 1 is a front elevational view of a pair of spectacles showing my new design;

Figure 2 is a rear elevational view thereof;

Figure 3 is a top plan view partly broken away for convenience of illustration; and

Figure 4 is a side elevational view.

I claim:

The ornamental design for a pair of spectacles or similar article, as shown.

EDWARD ROSEN.
